Filed Jan. 25, 1963, Ser. No. 73,321

Term of patent 7 years

(Cl. D33—14)

The brace arrangement on the side not disclosed in FIGURE 1 is the same as on the side shown.

The dominant feature of the design resides in the portions shown by full lines in the drawing.

This application is a continuation-in-part of my earlier filed co-pending cases Serial Nos. D. 67,107, D. 67,110 and D. 67,111, all filed October 16, 1961, and now abandoned.

I claim:

The ornamental design for a table, or a similar article, as shown and described.
